UNITED STATES PATENT OFFICE.

WILLIAM J. FEELEY, OF PROVIDENCE, RHODE ISLAND, ASSIGNOR TO APOSTLESHIP OF PRAYER, INCORPORATED, OF NEW YORK, N. Y., A CORPORATION OF NEW YORK.

DESIGN FOR AN EMBLEM FRAME.

Application filed September 14, 1927. Serial No. 23,407. Term of patent 14 years.

To all whom it may concern:

Be it known that I, WILLIAM J. FEELEY, a citizen of the United States, residing at Providence, in the county of Providence and State of Rhode Island, have invented a new, original, and ornamental Design for an Emblem Frame, of which the following is a specification, reference being had to the accompanying drawing, forming part thereof.

In the drawing:

I claim:

The ornamental design for an emblem frame, as shown.

WILLIAM J. FEELEY.
